UNITED STATES PATENT OFFICE.

GEORGE BAUSCH, OF SYRACUSE, NEW YORK.

DESIGN FOR AN EYEGLASS-GUARD.

SPECIFICATION forming part of Design No. 27,636, dated September 14, 1897.

Application filed January 14, 1897. Serial No. 619,251. Term of patent 7 years.

To all whom it may concern:

Be it known that I, GEORGE BAUSCH, a citizen of the United States, and a resident of Syracuse, in the county of Onondaga and State of New York, have invented a certain new and original Design for Eyeglass-Guards, of which the following is a specification.

The leading feature of my newly-designed eyeglass-guard consists in two planes offset from each other, forming two flat-faced members, one of which is shorter than the other, the said two members being united by a flat intermediate, forming two angles on a plane with each other, one angle being formed with each of the said members, the flat face of the lower member of the guard appearing roughened or hatched.

In the accompanying drawing, to which reference is made and which forms a part of this specification, the figure is a perspective view of my newly-designed eyeglass-guard.

In the drawing, A represents the lower flat member, and B represents the upper flat member, which is shorter than the said lower member and offset from the same, forming two angles a b , which are on a plane with each other, one of said angles being formed with each of said members A B. A plane flat surface c appears between said two angles a b , and the front surface of the said lower member A appears a facing having a roughened or hatched surface, as clearly shown in the drawing.

What I claim is—

The design for eyeglass-guards substantially as herein shown and described.

GEO. BAUSCH.
